UNITED STATES PATENT OFFICE.

LLOYD R. BRUCKNER, OF AUGUSTA, AND JOHN W. MURPHY, OF GRIFFIN, GEORGIA.

RURAL MAIL-CARRIER.

1,240,022.

Specification of Letters Patent. Patented Sept. 11, 1917.

Application filed August 21, 1916. Serial No. 116,162.

To all whom it may concern:

Be it known that we, LLOYD R. BRUCKNER and JOHN W. MURPHY, citizens of the United States, residing at Augusta and Griffin, respectively, in the counties of Richmond and Spalding, respectively, State of Georgia, have invented certain new and useful Improvements in Rural Mail-Carriers; and we do hereby declare the following to be 10 a full, clear, and exact description of the invention; such as will enable others skilled in the art to which it appertains to make and use the same.

This invention relates to improvements 15 in deposit and collection receptacles and is directed more particularly to an apparatus adapted for employment along rural delivery routes whereby to facilitate the delivery and collection of mail matter.

An object of the present invention is to 20 provide an apparatus of the above character in which the receptacle for the mail matter is normally disposed in a retracted position out of the path of passing vehicles and 25 which may be readily extended to a position within convenient reach of the occupant of a vehicle to permit the delivery or collection of mail matter without the necessity for dismounting from the vehicle or moving 30 the latter to a position off the road.

A further purpose of the invention is to 35 provide a means of novel construction and arrangement for supporting the mail receptacle whereby it may be adjusted to extended or retracted position with convenience and despatch.

With the above and other objects of similar nature in view, the invention consists in the construction combination and arrangement of parts, set forth in and falling within the scope of the appended claims.

In the drawing.

Figure 1 is a side elevation of an apparatus constructed in accordance with the 45 invention and in retracted position.

Fig. 2 is a top plan view thereof,

Fig. 3 is a detail side elevation with the parts in partially extended position and,

Fig. 4 is a vertical longitudinal section 50 with the parts in extended position.

Fig. 5 is a section on the line 5—5 of Fig. 4.

Referring now more particularly to the accompanying drawing, the device is illus-

trated generally at 10 and consists of a base 55 member 11 preferably in the form of a galvanized, tubular metal post.

The base 11 is disposed in an upright position and is rigidly supported either by sinking its lower end a suitable distance in 60 the ground, or by embedding said end in a concrete or like foundation provided for the purpose.

Swivelly mounted in the upper end of the base 11 is a stem 13, the lower end of which 65 is transversely cut away as at 14 to provide spaced shoulders 15 engageable by a set screw 16 threaded through the side of the post whereby to limit rotation of the stem in either direction. Carried by the upper 70 end of the stem and integral therewith is a head 17 longitudinally bifurcated as at 18 and provided with transversely aligned openings for receiving therethrough a pivot pin 20.

Supported for vertical swinging movement within the bifurcation of the head 17 and intermediately provided with an opening 22 to pivotally receive the pin 20 is an arm 21.

Slidably connected with the arm 21 at 80 one side of the base 11 is a carrier 23 adapted to move longitudinally of the arm in either direction when the latter is swung to extend at alternate angles above and below the horizontal. This carrier 23 is preferably 85 constructed of a pair of plates 24, the intermediate portions of which are connected by bolts 25 and are spaced apart a distance to receive there-between the arm 21 with the bolts 25 disposed respectively on 90 opposite sides thereof.

For holding the plates 24 in spaced relation there is engaged with one of the bolts 25 a spacing block 26 and rotatably supported by the other bolt a grooved pulley 95 27 adapted to ride upon the upper face of the arm when the same is swung to shift the carrier toward or away from the base. The carrier 23 terminates at each end in a yoke 28 formed by bending the plates 24 as 100 clearly illustrated. Pivotably supported within what is nominally the upper yoke of the carrier is a mail box 29 of conventional type, trunnions 30 being provided at opposite sides thereof for engagement 105 in bearing openings formed in the ends of the yoke and so disposed that no matter what position the carrier may assume the

box will maintain at all times an upright position.

The other or lower yoke 28 is somewhat smaller than the upper and carries a transverse bolt 32 from which is pivotally supported a bracket 33 so constructed as to support a second mail box 34 to which it is suitably secured.

This box 34 is also arranged to assume 10 at all times an upright position irrespective of the position of the carrier. For limiting movement of the carrier 23 outwardly of the arm there is carried at the terminal of the latter an eye bolt 35, the eye of which 15 is adapted for engagement by the hooked end of an operating member (not shown) whereby the arm may be conveniently swung to either of its positions by the occupant of a vehicle stationed on the road.

20 Slidably mounted on the arm 21 at the opposite side of the base from the carrier 23 is a counter weight 36 limited in outward movement by a bolt 37 at the end of the arm and held in adjusted position on the 25 latter by a binding screw 38. The counter weight 36 is adapted to hold the arm 21 at its upward limit of movement, with the carrier supported upon the head 17, in which position the boxes 28 and 34 are re- 30 tracted out of the path of passing vehicles.

It will be noted that when retracted, the carrier is resting in a substantially horizontal position upon the head 17 of the stem while the boxes 28 and 34 are disposed on 35 opposite sides of the base.

However in order to deliver mail to or receive mail from the boxes from a position on the road, the occupant of the vehicle carrying the mail will stop adjacent to the 40 box and, without leaving his vehicle, swing the arm 21 downwardly, by means of the operating member above referred to, at which time the carrier 23 will move under the influence of gravity to the end of the 45 arm while it will simultaneously rock or swing vertically with respect to the arm so that on reaching its limit of outward movement the position of the boxes 28 and 34 will have been reversed, the former ex- 50 tending beyond the end of the arm while the latter will extend inwardly toward the base 11.

When thus disposed, mail may be readily collected from and delivered to the boxes 55 after which the several parts of the apparatus may be again retracted by raising the arm 21 to permit the carrier and boxes to gravitate toward the base and again assume the position above described, such movement being facilitated by the counterweight 60 36 as is obvious.

By swiveling the arm 21 through the medium of the stem 13, a vehicle may be stopped at any reasonable distance to either 65 side of the base and the arm, swung hori-

zontally on the stem to bring the boxes within reach of the vehicle. This swiveling of the arm will result in a material saving of time in the operation of a mail route as it obviates the necessity for shifting the position of the vehicle when once a stop has been made.

Furthermore the proposed structure will permit the vehicle to remain in the road and the occupant to manipulate the boxes without dismounting, a distinct advantage particularly in wet weather when it is frequently necessary at the present time to either leave the vehicle or drive the same into a ditch at the side of the road, from which position it is extremely difficult to move should the vehicle be motor propelled.

What we claim is:

1. The combination with a base, of an arm 35 movable with respect thereto, and a receptacle carrier connected with the arm for movement thereon into positions for alternate direct support by the base and arm.

2. The combination with a base, of an arm movable to extend at alternate angles 90 with respect thereto, and a receptacle slidably carried by and shiftable on the arm to extend at alternate angles with respect to the arm and at opposite sides of the base.

3. The combination with a base, of an 95 arm pivoted intermediate its ends to the base, a carrier slidably mounted for rocking movement on the arm and limited in one direction by the base, receptacles supported by the carrier at opposite sides of the arm and 100 movable therewith to reverse their positions with respect to the ends of the arm, and a counterweight carried by the arm at the opposite side of the base from the carrier to normally maintain the carrier in engagement with the base and the receptacles at 105 opposite sides of the latter.

4. The combination with a base, of an arm movable with respect thereto, a carrier mounted on the arm for movement longitudinally thereof in both directions, receptacles supported by the carrier at opposite sides of the arm, and a counterweight on the arm arranged to normally maintain the same at its limit of movement in one direction and the carrier in close proximity to the base.

5. The combination with a base, of an arm movable with respect thereto, a carrier mounted to rock upon the arm and arranged 120 for movement longitudinally thereof to be limited in one direction by the base, and a receptacle supported by and movable with the carrier to reverse its position with respect to the base as the arm is moved in opposite directions.

6. The combination with a base, of an arm movable with respect thereto, a carrier movable longitudinally of the arm, and receptacles at opposite ends of the carrier 130

movable therewith to reverse their position with respect to the ends of the arm when the latter is moved in opposite directions.

7. The combination with a base, of an arm movable with respect thereto, a carrier slidably mounted on the arm for rocking movement, and a receptacle supported by the carrier and arranged in one position of the arm to extend outwardly beyond the end 10 thereof, and in the other position of the arm to extend inwardly of said end.

8. The combination with a base, of an arm movable with respect thereto, a carrier slidably mounted on the arm for swinging movement, and receptacles supported from the carrier on opposite sides of the arm, said carrier upon movement of the arm being arranged, at its limit of movement in either direction, to swing on said arm and reverse

the position of the receptacles with respect 20 to the ends of the arm.

9. The combination with a base, of a vertically swinging arm, and a carrier 25 slideable on the arm and arranged to swing vertically with respect thereto in its movement under the influence of gravity toward opposite ends of the arm as the latter is swung.

In testimony whereof, we affix our signatures in the presence of two witnesses.
